ADJUSTABLE LOUVER

James E. Murphy, Helmuth W. Schmitz, and
Alexander M. Peabody, Seattle, Wash.

Application January 22, 1934, Serial No. 707,690

1 Claim. (Cl. 98—121)

This invention relates to louvers and it has reference more particularly to louvers of that character designed for application to wall openings for purposes of ventilation and for admitting 5 tance of light; the device of this invention being especially applicable to window transoms or other wall openings, as provided in passenger carrying ships and railway cars, for purposes of obtaining light and proper ventilation.

10 It is the principal object of the invention to provide a device embodying a plurality of co-operatively arranged, pivotally adjustable louver panels mounted in a frame structure that is applicable to a wall opening as a unit structure, and 15 including means for effecting a simultaneous adjustment of all the louver panels between open and closed positions.

It is also an object of the invention to provide 20 a louver structure in which the panels are mounted in parallel relation and have supporting pivots at their opposite ends in axial alinement and wherein all the panels may be adjusted into the same plane, in edge to edge relation, to completely close the opening to which they are applied or may be adjusted toward either side of the 25 said plane to various angular positions between closed and fully opened positions.

Another object of the invention resides in the 30 rounding of the adjacent edges of the louver panels to provide for their coming in close relation for film sealing when moved to closed position.

Other objects of the invention reside in the 35 details of construction of the various parts, in their relationship, and in their means for and mode of operation, as will hereinafter be fully described.

In accomplishing these and other objects of the invention, we have provided the improved details of construction, the preferred forms of which are 40 illustrated in the accompanying drawings, wherein—

Fig. 1 is an elevation of the present louver as applied to a window opening; the illustration showing the device from the outside.

45 Fig. 2 is a horizontal section, as seen on line 2—2 in Fig. 1.

Fig. 3 is a vertical, cross section, taken on line 3—3 in Fig. 1.

Fig. 4 is a cross sectional detail of the upper or 50 head portion, taken on line 4—4 in Fig. 1.

Fig. 5 is a cross sectional detail taken on line 55 5—5 in Fig. 1.

Fig. 6 is a sectional detail illustrating the rounding of the panel edges for obtaining a close fitting joint for film sealing.

Fig. 7 is a view diagrammatically illustrating a 5 mechanical means employing cylinders and a fluid pressure medium for actuating the louver panels of a series of openings between open and closed position.

Fig. 8 is a similar view illustrating a cable connection for actuating the panels of a plurality of louvers.

Referring more in detail to the drawings—

The louver, in its present form of construction, 10 comprises a rectangular frame structure of sheet metal and of such dimensions that it will closely fit within the opening to which it is to be applied. This frame comprises a lower sill portion 2, opposite side portions 3—3' and a top or head portion 4; each of which parts is provided with an inturned flange 5 about its inner edge, as seen in Fig. 3, and with an out-turned flange 6 about its outer edge for reception of screws, or the like, 15 7 for securing the frame to the enclosing framing, including the wooden top and bottom members 8 and 9 seen in Fig. 3 and the opposite side rails 10 and 10', as seen in Fig. 2. Suitable casings, as at 11 may be provided about the louver frame to present an attractive finish to the open- 20 ing.

The opening provided within the frame structure of the louver is of rectangular form and is fitted with a plurality of vertically arranged and parallel louver panels 12, preferably of glass. 30 Each panel is seated at its upper and lower ends, respectively, in grooved mounting bars 13—13' each of which has a central pivot member. The pivot members 14 and 14', respectively, of corresponding upper and lower bars are in axial alinement and the several panels pivot in either direction about parallel axes.

A metal bar 16 is secured longitudinally of the frame upon the sill portion 2 for re-enforcing and this is provided with sockets 17 in which the pivots 14' of the lower panel mounting bars 13' are revolvably contained. The pivots 14 of the upper bars 13 consist of short shafts that extend revolvably through openings 18 in the head portion 4 and also through openings 19, registering therewith, formed in a re-enforcing plate 20 secured longitudinally upon the head portion 4, as seen in Fig. 2. These latter pivots 14 have gear wheels 21 fixed thereon to mesh with teeth 22 of a rack bar 23 that is slidably movable in guides 24 fixed upon the plate 20. 45

The bar 23 at a central point has a gear toothed top surface 25 with which a gear wheel 26 meshes. Wheel 26 is fixed on a shaft 27 mounted in bearings 28 fixed to plate 20 and it extends to the 55

inside of the frame where it is equipped with a hand wheel 30.

The construction above described provides that upon manual rotation of the hand wheel, in opposite directions, the rack bar 23 will be shifted accordingly in an endwise direction. The shifting of this bar effects a like rotative movement of all gears 21 and thus simultaneously effects a rotative adjustment of the louver panels, which 10 may be swung from neutral position, at which they completely close the opening, as seen in Fig. 1, to different angular positions as illustrated in dotted lines in Fig. 2.

It will be observed by reference to Fig. 6 that 15 adjacent edges of the panels are rounded off arcuately as at 35 about the axial lines of the panels. Thus, they are permitted to be brought substantially into line contact, or sufficiently close that the joint between them can be sealed by a 20 water film. This is advantageous as it provides for tightly closing the louver by an adjustment whereby all panels are brought into the same 25 plane and thus avoids necessity of overlapping the panel edges which would limit the adjustment of the panels to one direction.

In Figs. 7 and 8 we have illustrated diagrammatically means for automatic actuation of a series of louvers. As shown in Fig. 7, there is a cylinder 40 associated with each louver. Piston 41 30 is reciprocally contained in the cylinder and connected by a link 42 with a lever arm 43 fixed on the hand wheel shaft 27. Pressure medium supplied by a pipe 45 is adapted to be admitted through a valve device 46 and pipes 47-48 to 35 the cylinder at opposite sides of the piston to actuate it in opposite directions. The valve is a four-way construction and by its manipulation the louver panels may be adjusted in opposite directions from closed position. One valve may 40 control the application of pressure medium to the cylinders of a series of louvers.

In Fig. 8 is another form wherein a cable belt 50 is extended about wheels 51 and 52 and along a series of louvers and the levers 43 of the several 45 louvers are connected to the lower run of the cable for simultaneous operation which is effected by rotation of the wheel 51.

In both of the alternative devices as illustrated in Figs. 7 and 8, the shaft 27 would be connected by suitable gearing with a bar 23 which would connect with the louvers in any suitable manner, for example as illustrated in Figs. 1 and 2.

Louvers of the character disclosed are very desirable for the reason that they permit passage of light therethrough in either open or closed positions; they may be adjusted to accommodate wind direction and either to withdraw or drive 10 air into the room to which they are applied. When closed, they effectively keep out rain as the water seals the close joints between closed panels. Water which might seep through the 15 panel joints is drained back to the outside through perforations 60 in the base bar as seen in Fig. 1, since the upturned flange prevents its flowing to the inside.

Having thus described our invention, what we 20 claim as new therein and desire to secure by Letters Patent is—

In a louver construction, a metallic frame structure fitted in a wall opening and having top and bottom sills said bottom sill having an upturned 25 flange along its inner edge, a rail fixed lengthwise of the sill and spaced from the flange, and provided with drainage ports therethrough from its inner to its outer side, a plurality of louver panels arranged vertically in said frame and 30 having mounting pivots centrally at the upper and lower ends; the lower pivots being mounted in said rail and the upper pivots extending through said top sill, gear wheels fixed on said pivots above the top sill, a rack bar slideable on 35 said sill and meshing with said gear wheels, manual means for shifting the rack to effect rotative adjustment of the louver panels; said panels having parallel axes and parallel opposite side edges, and said edges being arcuately curved 40 about their axes, whereby edges of adjacent panels may be brought substantially into line contact for film sealing.
